GAME BOARD

Charles P. Chalcroft, 815 25th Ave. W., Eugene, Oreg.

Filed Apr. 8, 1960, Ser. No. 60,100

Term of patent 14 years

(Cl. D34—5)

I claim:

The ornamental design for a game board, as shown.
